(57) **CLAIM**

The ornamental design for a saw blade package and carry case, as shown and described.

DESCRIPTION

FIG. 1 is a front perspective view of the saw blade package and carry case;

FIG. 2 is a front plan view of the saw blade package and carry case of FIG. 1;

FIG. 3 is a rear perspective view of the saw blade package and carry case of FIG. 1;

FIG. 4 is a rear plan view of the saw blade package and carry case of FIG. 1;

FIG. 5 is a side view of the saw blade package and carry case of FIG. 1, both sides being identical;

FIG. 6 is a top view of the saw blade package and carry case of FIG. 1;

FIG. 7 is a bottom view of the saw blade package and carry case of FIG. 1;

FIG. 8 is a front perspective view of the saw blade package and carry case of FIG. 1 holding a quantity of saw blades; FIG. 9 is a front perspective view of the saw blade package and carry case of FIG. 1 holding a quantity of saw blades different than the quantity in FIG. 8; and,

FIG. 10 is a front perspective view of an alternate embodiment of the saw blade carry case showing a covering around the perimeter of the carry case.

The broken line showings of the saw blade and the indicia are for illustrative purposes only and form no part of the claimed design.
